APPARATUS FOR MAKING PLUG BRICKS

John B. Blewett, Wellsville, Ohio, assignor to
The McLain Fire Brick Company, Pittsburgh,
Pa., a corporation of Delaware

Application July 22, 1943, Serial No. 495,725

7 Claims. (Cl. 25—44)

The present invention relates to an apparatus for the manufacture of plug bricks with an expanded hole.

The primary object of the invention is to provide an attachment for a plug brick machine having a spinner head, which attachment is adapted to be carried by the head to form an opening centrally of the plug brick terminating in an interior enlarged opening.

A further object of the invention is to provide suitable apparatus for forming plug bricks used in connection with ingot molds so that when the molten metal is poured in the mold, a portion of the metal will flow into the enlarged cavity in the plug brick and anchor the same to the bottom of the ingot.

A still further object of the invention is to provide an apparatus which may be easily attached to the spinner head of an ingot mold plug brick forming machine without requiring excessive alterations to the mold or to the spinner press head.

A still further object of the invention is to provide an attachment for an ingot mold plug brick machine which is entirely automatic in operation and requires very little manual attention such as for the purpose of making adjustments to increase the depth of the opening in the center of the plug brick.

Other objects and advantages of the invention will become apparent during the course of the following description of the accompanying drawings wherein:

Figure 1 is a top plan view of the attachment embodying the invention.

Figure 2 is a side elevational view of the same showing the manner in which the presser head is carried by the attaching supporting member.

Figure 3 is a vertical cross sectional view taken at right angles to Figure 2, showing in detail the pivoted former and the mode of its operation.

Figure 4 is a side elevational view of the attachment showing the presser head in its compressed position for laterally moving the former after it has been projected into the plug brick.

Figure 5 is a vertical cross sectional view taken at right angles to Figure 4, illustrating the former in its operative position with respect to the plug brick.

Figure 6 is a top plan view of the plug brick formed in the apparatus, and

Figure 7 is a fragmentary side elevational view of the finished ingot mold plug brick illustrating the shape of the central opening formed therein.

In the drawings, wherein for the purpose of

illustrating the invention and wherein like reference characters will be employed to designate like parts throughout the same, the reference character 10 will generally be employed to designate one of the mold cavities of a plug brick machine which may be mounted on a turn-table and be provided with suitable mechanism for raising and lowering the mold members 10 as they reach predetermined stations. One of such stations 10 comprises a spinner head which is rotated so that when the mold cavity 10 and plastic refractory material 12 is raised into engagement therewith, the upper surface of the mass 12 will be smoothed and devoid of any flaws.

15 A bottom wall 14 is usually provided for the mold members 10 and is of circular shape to fit within the bottom thereof.

The invention comprises a carrier 16 having a circular boss 18 formed on the top thereof 20 which is adapted to be attached as by means of machine screws suitably carried by the spinner head (not shown) threaded in the openings 20 of the circular boss 18. The carrier 16 is circular and is provided adjacent its periphery with 25 a series of bolts 22 having heads 24 to limit the downward movement of the bolts 22 with respect to the carrier 16.

Supported by the lower ends of the bolts 22 is a circular presser plate 26 having openings 30 through which the threaded ends 28 of the bolts 22 extend so that nuts 30 may be threaded thereon and prevent displacement of the presser plate.

35 Mounted on each of the bolts 22 between the carrier 16 and presser plate 26 is a coil spring 32 which is adapted to be compressed when the presser plate 26 is moved upwardly when engaged by the upper edge of the mold member 10.

Formed in the circular boss 18 is a diametrically arranged cavity 34 which is adapted to house the upper end of a former bar 36 pivoted to the presser plate 26 by means of a pivot pin 38 extending through oppositely arranged angle brackets 40 secured in place on opposite sides of an elongated slot 42 formed centrally with respect 45 to the presser plate 26. It is noted that the former bar 36 projects downwardly through said opening and operates in a bifurcated plunger 44 which is secured to the underside of the presser plate 26 as by means of welding or the like.

50 The upper end of the former rod 36 projects through a slot 46 in the carrier head 16 and terminates within the cavity 34. Attached to opposite sides of the slot 46 is a pair of angle brackets 48 arranged in opposed relation adapted to receive a guide pin 50 operating in a diag-

onal cam slot 52 formed in the upper end of the former bar 36.

The lower end of the former bar 36 is slightly offset as at 54 and is adapted to be provided with a collar 56 pivoted thereto as at 58.

Also secured to the underside of the carrier 16 is a pair of parallel blocks 60 mounted on opposite sides of the former bar 36 to limit the upward travel of the presser plate 26 when engaged by the mold member 10 during its upward travel.

In operation, the mold cavity members 10 are stopped on their turn-table to receive a mass of plastic refractory material 12 which is then moved to a position under the carrier 16, whereupon the mold cavity member 10 is automatically raised so that the plunger 44 and lower end of the former bar 36 will enter the mass 12 and produce a central opening 62 therein as shown in the finished article in Figures 6 and 7.

Upon continued upward travel of the mold cavity member 10, the presser head 26 is moved upwardly against the action of the coil springs 32, whereby the former bar 36 will be raised with respect to the rotating carrier 16 so that the pin 50 will operate in the cam slot 52 to tilt the lower end of the former bar 36 to cause the collar 56 to enlarge the opening 62 as at 64 as shown in Figures 6 and 7.

When the mold cavity member 10 moves downwardly and away from the presser plate 26, the former bar 36 will return to its perpendicular position, whereby the collar 56 will be within the confines of the tubular bifurcated plunger 44 thereby allowing the continued lowering of the mold cavity member 10 until the plunger 44 and lower end 54 of the former bar 36 are withdrawn from the plastic mass 12 through the restricted opening 62 therein.

It is to be understood that the form of the invention herewith shown and described is to be taken as a preferred embodiment of the same and that various changes in the shape, size and arrangement of parts may be resorted to without departing from the spirit of the invention or the scope of the subjoined claims.

What is claimed is:

1. For use with a plug brick mold, a carrier adapted to be supported by a spinner head, a presser plate adapted to be engaged by the mold, and a former plunger pivoted to the presser plate and adapted to form an offset cavity in the material carried by the mold.

2. For use with a plug brick mold, a carrier adapted to be attached to a spinner head, a presser plate resiliently supported by the carrier and adapted to be engaged by the mold, and a cam operated lever extending through the carrier and pivoted to the presser plate and adapted to form an offset opening in the material in the mold.

3. For use with a plug brick mold, a carrier

adapted to be attached to a spinner head, a presser plate resiliently supported by the carrier, and a pivoted former lever carried by the presser plate and adapted to be tilted upon relative movement between the presser plate and carrier to form an offset opening in the material being molded.

4. For use with a plug brick mold, a carrier adapted to be attached to a spinner head, a presser plate adapted to be engaged by the upward travel of the mold, a former bar pivoted to the presser plate and having an end extending into the mold, and cam means carried by the carrier for tilting the former bar upon relative movement between the presser plate and carrier.

5. For use with a plug brick mold, a carrier adapted to be attached to a spinner head, a presser plate resiliently suspended from the carrier and adapted to be engaged by the mold, a former lever pivoted to the presser plate and having its lower end extending into the mold cavity and its upper end projecting through a slot in the carrier, a pin and slot connecting between the upper end of the former lever and the carrier to rock the lever upon relative movement between the presser plate and carrier, and a collar attached to the lower end of the said former lever and adapted to form an enlarged cavity in the material being molded.

6. For use with a plug brick mold, a carrier adapted to be attached to a spinner head, a presser plate resiliently suspended from the carrier and adapted to be engaged by the mold, a former lever pivoted to the presser plate and having its lower end extending therethrough and into the mold cavity, and having its upper end projecting through a slot in the carrier, a pin and slot connection between the former lever and the carrier adapted to rock the former lever on its pivot, a bifurcated plunger carried by the presser plate at approximately the lower end of the former lever, and a collar mounted on the lower end of the former lever and adapted to produce an enlarged cavity in the material being molded.

7. For use with a plug brick mold, a circular carrier adapted to be attached to a spinner head, a presser plate slidably supported by the carrier and adapted to be engaged by the mold, spring means for holding the presser plate away from the carrier, a bifurcated plunger mounted on the lower side of the presser plate, a former lever pivoted to the presser plate and extending through an opening therein and between the legs of the bifurcated plunger, a former collar located on the lower end of the said former lever and adapted to produce an enlarged opening in the material being molded when the former lever is rocked by the upward travel of the presser plate.

JOHN B. BLEWETT.
